(57) **CLAIM**

The ornamental design for a flowmeter, as shown and described.

DESCRIPTION

FIG. 1 is a top and front perspective view of a first embodiment of a flowmeter, showing our new design; FIG. 2 is a rear perspective view thereof; FIG. 3 is a top view thereof; FIG. 4 is a bottom view thereof; FIG. 5 is a right side perspective view thereof; FIG. 6 is a left side perspective view thereof; FIG. 7 is a top, rear and left side perspective view thereof; and FIG. 8 is a top, front and right side perspective view thereof. FIG. 9 is a top, front and left side perspective view thereof. FIG. 10 is a top and front perspective view of a second embodiment of a flowmeter, showing our new design; FIG. 11 is a rear perspective view thereof; FIG. 12 is a top view thereof; FIG. 13 is a bottom view thereof; FIG. 14 is a right side perspective view thereof; FIG. 15 is a left side perspective view thereof; FIG. 16 is a top, rear and left side perspective view thereof; and FIG. 17 is a top, front and right side perspective view thereof. FIG. 18 is a top, front and left side perspective view thereof. FIG. 19 is a front perspective view of a third embodiment of a flowmeter, showing our new design; FIG. 20 is a rear perspective view thereof; FIG. 21 is a top view thereof; FIG. 22 is a bottom view thereof; FIG. 23 is a right side perspective view thereof; FIG. 24 is a left side perspective view thereof; FIG. 25 is a top, rear and left side perspective view thereof; and FIG. 26 is a top, front and right side perspective view thereof; and, FIG. 27 is a top, front and left side perspective view thereof. The broken line portion in the drawings is included to show unclaimed subject matter only and forms no part of the claimed design.
